RETICULATED SHEET METAL SIGN

Thornton J. Simpson, Chula Vista, Calif., assignor of one-half to W. Colston Bartlett, Chula Vista, Calif.

Application March 20, 1939, Serial No. 262,895

3 Claims. (Cl. 40—130)

This invention relates to a light reflecting sign, the lettering of which is outlined upon reticulated sheet metal.

Among the objects of the invention are: To provide for the erection and maintenance of a large, illuminated sign at a relatively low cost; to provide a very durable sign that will better withstand stormy weather, including the effects of moisture and heavy winds; and to provide a sign in which the lettering will stand out conspicuously without the visual impression made thereby being minimized by other objects being noticeable near thereto or in the background thereof.

It is also an object of the invention to provide a sign reflective material which will give back to the observer the colors of the lights directed thereagainst.

Other objects, advantages, and features of invention will hereinafter appear.

Referring to the accompanying drawing, which illustrates what is at present deemed to be a preferred embodiment of the invention,

Fig. 1 is a view, somewhat in perspective, showing the sign and its illuminating means installed adjacent to a street and railway intersection to warn traffic approaching the railway in one direction, it being understood that the same sign equipment will be duplicated at the opposite side of the street and railway to warn traffic moving in the opposite direction.

Fig. 2 is a side elevation of the sign equipment shown in Fig. 1.

Fig. 3 is a face view on a greatly enlarged scale, of a fragment of the reticulated sheet metal whereon is outlined a fragment of the lettering carried by the sign. The observer is presumed to be directing his vision upwardly at an angle of 45 degrees.

Fig. 4 is a cross section on line 4—4 of Fig. 3. Referring in detail to the drawing, a reticulated metal sheet 10, which may be manufactured by a well known cutting and stretching operation, is shown mounted upon and within a panel 11 which is supported by posts 12 in a conspicuous manner adjacent to the intersection of a railway 13 with street 14. A source of light 15 is provided from which light rays 16 are projected upon the sign.

As shown in detail in Fig. 4, the reticulated metal sheet 10, known as "metal lath", has the diagonally intersecting strand portions 17 and 18 which, in relation to their breadths as well as to their lengths, are inclined in relation to the plane occupied by the sheet as a whole, so

as to cause the light rays 16 to strike their side portions or faces in a more direct manner, that is to say, with an angle of incidence more nearly approaching ninety degrees. Also, the widened metal portions 19 at the intersections of the strands provide inclined, light reflecting surfaces, while the openings 20 allow unreflected light to pass through, so that the observer sees the lettering of the sign in an isolated, apparently unsupported position.

Referring to Fig. 3, it will be observed that the face nearest to the observer of the inclined strand section at the upper right-hand side of each of the openings 20, (that is to say, leading upward and leftward from any one intersection area 19 to the next left-hand intersection area 19), is directed not only downwardly, but also toward the observer's left, while the corresponding strand section at the left side of each opening is directed, not only downwardly, but also toward the observer's right. But, as the source of light is located directly in front of the sign, both of these inclined sections are equally illuminated.

The acute angles at the right and left ends 25 of the openings 18 are designated 18b, and the obtuse angles above and below are designated 18c.

The lettering 21 of the stop warning which is shown inscribed upon the sign is outlined upon 30 said inclined strand portions, as it is only the part of the sign occupied by them that is available for being used for image forming purposes. The letters may be outlined as unpainted surfaces which are surrounded by an area painted 35 with dark paint. But after the dark paint has been applied, the visibility of letter outlining areas may be enhanced by applying a coat of aluminous paint or other light-colored paint to them.

The reticulated member 10 may be made of aluminum or of stainless steel. The use of aluminum paint upon the face of the lettering will not be necessary when said member is constructed of aluminum.

The particular area of the reticulated sheet metal shown in Fig. 3 may be taken as representing the lower part of the stem of one of the T's of the subject matter of the sign, the darkened metal areas d on each side edge portion of the 50 view being painted or surface treated to render them non-reflective to the light, while the side portions of the stem of the T are defined by the lines of demarcation e between the areas which are reflective and non-reflective of light. 55

The lighting means 15 may be of any desired conventional character. Separately considered, just how this light may be produced and timed forms no part of the invention. It may be constructed and arranged to be activated only when an approaching train nears the intersection, well-known electrical connections with the rails of the track 13 being utilized for this purpose. It may continuously direct light rays upon the sign. But it is deemed preferable that said lighting means be used to alternately direct differently colored light rays upon the sign.

With this end in view, the housing 25, which is supported by a post 26, is shown having an upper lens 27 and a lower lens 28, both directed 15 towards the sign, the position of the illuminating means 15 being such that the light rays will encounter the sign at an upward inclination of about forty-five degrees. Amber rays will desirably be afforded by the upper lens 27 and red rays by the lower lens 28, and, by a suitably timed 20 mechanism, (which may be contained within the housing 25) these differently colored light rays will be thrown upon the sign in alternation.

The upper front lamp 29, desirably amber, and lower front lamp 30, desirably red, are serviceable 25 as a means for initially attracting the attention of pedestrians and autoists to the sign. The preferred cycle of operation of the four lamps, as 30 represented by their reference numerals in Fig. 2, is 30, 28, 29, 27.

While the reticulated sheet of metal 10 shown in the drawing is at present deemed preferable as a placard forming means on which to inscribe the subject matter of the sign, yet an otherwise 35 foraminated sheet of rigid material having intact portions or webs with faces properly inclined in relation to the source of light could be used for the same purpose without departing from the 40 spirit of the claimed invention.

The material of which the sign proper 10 is constructed is of such a character that it gives back to the observer the same color of light as that which is directed thereupon, whether it be 45 red, amber, or some other color.

It should be understood that the present disclosure is for the purpose of illustration only and that this invention includes all modifications and

equivalents which fall within the scope of the subject matter claimed.

What is claimed is:

1. In a sign structure, a reticulated metal sheet having portions which are of light reflecting character surrounded by portions non-reflective to light, said reflecting portions being shaped to outline letters, characters, or objects forming the subject matter of the sign, and a source of light to direct light upon said metal sheet to cause said subject matter thereof to become visible, the reticulated metal of the sign having strands, the light reflecting surfaces of which are inclined in relation to the face of the sheet, and the light rays from said source of light being inclined in relation to the face of the sign in order to encounter said light reflecting surfaces in a more right-angled manner.

2. In a sign structure, a reticulated sheet of rigid material, the strands of which are of a flat, strap-like form, said strands having face portions which are similarly inclined in relation to the face of the sheet as a whole, the subject matter of the sign being outlined upon said inclined faces by rendering some portions of them reflective, and the others non-reflective of light, means to support said sheet in an elevated, substantially vertical position, and light supplying means located downwardly from said sheet to direct rays of light upwardly thereupon to illuminate the 30 aforesaid lettering outlined thereupon.

3. In a sign structure, a sheet of material of a foraminated character, the intact portions of which form a multiplicity of faces which are inclined in a generally uniform manner in relation to one edge portion of the sheet, the subject matter of the sign being outlined upon said inclined faces by surface conditions, rendering some portions of them reflective and other portions non-reflective to light, means supporting said sheet above the ground level, and means whereby light is directed upwardly from a point adjacent to the ground level upon the subject matter of the sign, the last recited means also emitting light rays in the opposite direction to those falling 45 upon the sign to attract the attention of observers approaching the sign.

THORNTON J. SIMPSON.
